SUPPORT FRAME FOR A TABLE OR SIMILAR ARTICLE

Joseph Ricca, 323 12th St., Cresskill, N.J. 07626

Filed Oct. 23, 1967, Ser. No. 9,116

Term of patent 14 years

Int. Cl. D6—01

U.S. Cl. D33—14

The figure is a perspective view of a support frame for a table or similar article, showing my new design.

The frame is characterized by the flat top in combination with the severely arched leg members and the centrally disposed hub on the leg brace unit, all as shown.

I claim:

The ornamental design for a support frame for a table or similar article, as shown and described.
